PAPER GLAZING MACHINE

Walter E. Brown, Reiffton, Pa., assignor to Wyoming Glazed Paper Company, West Reading, Pa., a corporation of Pennsylvania

Application October 3, 1934, Serial No. 746,684

8 Claims. (Cl. 92—72)

My invention relates to paper glazing machines of the nature indicated in C. M. Hallman's United States Letters Patent, No. 1,357,234, dated November 2, 1920, issued to the assignee of this application; and, more particularly, it consists in improvements in the pressure tensioning of the reciprocated radius-bar polisher, and in the construction and mounting of the paper-supporting bed, whereby I am enabled to operate the machine at a greatly increased speed and economically produce a high quality glazed sheet of uniform color and thickness throughout its entire width.

In machines of this nature, in which the polishing bar reciprocatively swings in a radial arc from its pivotal connection on a spring carrier-beam, and frictionally engages the continuously fed paper passing over a flat supporting-bed, the primary difficulty is to secure a uniform rubbing action across the entire width of the passing paper. Due to such construction the frictional pressure of the polishing bar varies across the width of the paper, with its greatest pressure normally exerted in its vertical position midway of its reciprocal swings, the diminishing pressure toward each edge of the paper exerting less glazing action with resultant lack of uniformity of surface color and uneven paper thickness.

The Hallman patent referred to above, provided means for more equally distributing the pressure of the radius bar polisher, but I have found in practice, that when the speed of operation is increased as desirable for increased economical production, a material change occurs in the points of greatest pressure of the radially swinging pressure bar. Such variance in pressure, is most clearly discernible in piled-up sheets of the differently produced papers,—those produced by slow movement of the polisher bar sagging midway of the paper width due to the pressure at such point reducing the thickness of the paper; and contrary, those produced by increased speed of the polisher bar, projecting upward at such mid-width point, with both edges sagging due to reduced thickness, clearly disclosing shifting toward such edges of the greatest pressure points.

This shifting of the pressure points at high speed is a demonstrable fact, which may be accounted for by varying theories, but I have found means to counteract this shift and satisfactorily uniformly distribute the pressure of the radius bar, and my present improvements relate to such means, and will be more fully described in connection with the accompanying drawing, and the

novel features thereof set forth in the appended claims.

Fig. 1 indicates diagrammatically, in front elevation, a machine of the nature shown in said Hallman Patent No. 1,357,234, and discloses in connection therewith a prepared embodiment of my improvements for overcoming the aforesaid shift of the pressure points when the machine is operated at high speed.

Fig. 2 is an enlarged cross-section detail view, 10 taken on the line 2—2 of Fig. 1, showing the adjustable tensioned rest for the free end of the spring pressure-beam.

Fig. 3 is an enlarged cross-sectional detail view, 15 taken on the line 3—3 of Fig. 1, showing the construction of the flat paper-supporting bed.

Figs. 4, 5 and 6, are diagrammatic views indicating respectively piled up sheets made by, first, slow movement of the radius-bar polisher; second, by fast movement of said polisher; and, 20 third, by fast movement of said polisher with my improvements applied to the machine.

The machine indicated in the drawings essentially comprises, as heretofore, a reciprocable radius bar 6, pivotally suspended at 7, from a 25 spring carrier-beam 8, and its lower end clampingly gripped flinting stone 9 is transversely swung, as by crank wheel 10 and pitman 11, across a width of paper fed over a flat paper-supporting bed 12. The paper, indicated by dotted lines 13, 30 is progressively fed forward by any usual means not necessary to show, and it will be readily understood that best glazing action of the flinting stone requires accurate adjustment and satisfactory uniform frictional pressure of the stone 35 across the entire width of the paper to secure even glazing results on the color coated surface and avoid uneven paper thickness.

The provisions of the aforesaid Hallman patent provided for satisfactory results at a given speed 40 of paper feed and reciprocation of the radius-bar polisher. Without adequate provision for equalizing the action of the radius bar, slow movement tends to thin the paper midway of its width, causing a concave surface when sheets are piled one 45 upon another as indicated in Fig. 4. Increase of speed tends, as heretofore described, to shift such paper thinning to the lateral edges, causing a convex surface in piled up sheets, as indicated in Fig. 5. Neither concave nor convex sheets are 50 satisfactory especially when the paper is intended to be fed to automatic printing presses.

Fig. 6 indicates desirable flat piling up of satisfactorily uniformly treated sheets, and whatever explanation may be advanced to account for ac- 55

tual shifts of the pressure points at increased speeds, I have found that such satisfactory results may be practically secured at speed increase approximately one-third or more than that heretofore found practical, by employment of my machine improvements, the preferred embodiment shown in the drawing, and now to be fully described, comprising a counter-acting tensioning means or resilient rest for one end of the spring carrier-beam, and a resilient surface and special mounting for the flat paper-supporting bed.

Adjustable frictional pressure of radius bar 6 is provided, as heretofore, by tension applied, as by screw-jack 15, to carrier-beam 8, intermediate 15 its length, and one end of said bar, held in a fixed supporting bracket 16, and the radius-bar pivotal connection 7, secured adjacent the other end of said bar. At the radius-bar end of said beam 8, heretofore left free to vibrate, I have 20 shown in the drawing a resilient support in the form of a fixed carrier-bracket 17, having a vertical slide-way for a beam rest plate 18, movably held in contact with the under side of said vibrating beam-end by resilient means, shown as 25 springs 19 engaging between said plate 18 and a platform 20 adjustable, as by screw 21, relative to plate 18 to regulate the tension of said springs 19.

The actual and demonstrable shift of excess 30 pressure of the radius-bar polisher from midway to the lateral edges of the paper, when the speed of operation is increased, is probably best accounted for by rebounding tendency of the more frequently vibrated beam-end, and perhaps a 35 push and pull influence through the pitman reciprocating the radius-bar. but whatever the cause, by resiliently supporting the vibrating beam-end, as above described, excess pressure at the lateral edges may be counteractingly controlled. In 40 practice I have found that by raising the spring platform by the adjusting screw 21 to increase the tension of the springs 19, the excess pressure is moved laterally inward toward the center of the paper; and contrary, by weakening the 45 springs, the excess pressure moves outwardly toward the edges of the paper.

To cooperate in the production of better output, I have found it advantageous to reconstruct and mount the paper-supporting bed 12, which 50 is of a length to support the widest paper to be operated upon and a narrow width in the direction of the paper feed sufficient only to form a support beneath the reciprocated flinting stone 9. As shown the bed is formed of a suitable length 55 of proper-sized wood 25, thickened or immediately reenforced on its under side for a major portion of its length by a strip of wood 26 of similar cross-section, and its upper surface having ends blocks 27, 27 spacedly carrying a metal strip 28 upon which is preferably secured a paper or wood fibre wearing strip 29 on which the paper rests; and the space between the metal strip 28 and bed wood 25 is preferably filled by a suitable strip 30 of non-conducting cushioning material, 60 as cork or the like. The metal strip 28, between its end supports 27, 27, tends to bend under the pressure of the reciprocated radius bar 6, and this bending action is cushioned by the resilient strip 30, which further insulates the bed wood 25 65 from any heat developed by the friction of flinting stone 9. And further, in order that the bed 12 may have any needed further resilience of spring in its wood members 25 and 26, I preferably mount the bed, as shown, in end carrier brackets 70 35, 35 secured respectively to spaced supporting

standards 36, 36; said brackets having inclined rests 37, 37 engaging only the extreme ends of the bed wood 25, which ends may have metal wear plates if desired, and provide bed-centering screws 38, 38 in the respective brackets 35, 35. This extreme end support of the bed 25 not only provides for maximum resilience of its paper supporting surface, but also provides for very accurately adjusting the position of the latter relative to the reciprocating flinting stone 9, and in practice cooperates with the resilient support for the end of the spring beam 8 to produce an equalized flinting action on the paper across the entire width of the latter.

This improved mounting of the novel paper-supporting bed 12 providing a pressure yielding resistance to the action of the radius bar polisher 6 reciprocatively traversing its width, I find essentially aids and cooperates with the resilient control of the spring beam vibrations, and enable 15 me to satisfactorily secure a practical equalization of the frictional pressure of the flinting stone 9 across the entire width of the forwardly fed paper strip 13, with the result of a glazed surface of more uniform color and an even paper 20 thickness, with a material increase in output at the higher speed of operation I am enabled to obtain.

The preferred embodiment of my invention above fully described, operates in actual production with most satisfactory results, but it is obvious that modifications of the construction described may secure equally satisfactory results. For instance, it is conceivable that the spring beam end 35 may be left free to vibrate, and supports of the resilient nature shown for such end, be applied instead to each end of the paper supporting bed 12 in lieu of, or in conjunction with, the inclined rests 37, 37 described as supports for said bed. Other modifications may later occur, and it is my intention to include any such modifications that 40 may be developed within the spirit of my invention as set forth in the following claims.

What I claim is:

1. In a machine for glazing continuously-fed 45 paper or the like comprising a flat paper-supporting bed, a transversely reciprocable radius-bar polisher, a spring carrier beam for the latter provided with tensioning means to regulate the pressure applied to the paper by said polisher, and 50 means to rapidly reciprocate said radius bar; means to approximately equalize the pressure of said polisher in its movement across said paper comprising a yielding bed, a paper supporting plate, and a non-heat conducting resilient cushion 55 interposed between said paper supporting plate and said yielding bed.

2. In a machine for glazing continuously-fed 60 paper or the like comprising a flat paper-supporting bed, a transversely reciprocable radius-bar polisher, a spring carrier beam for the latter provided with tensioning means to regulate the pressure applied to the paper by said polisher, and 65 means to rapidly reciprocate said radius bar; means to approximately equalize the pressure of said polisher in its movement across said paper comprising a vibration controlling spring-tensioned support for the end of said spring carrier beam.

3. In a machine for glazing continuously-fed 70 paper or the like comprising a flat paper-supporting bed, a transversely reciprocable radius-bar polisher, a spring carrier beam for the latter provided with tensioning means to regulate the pressure applied to the paper by said polisher, and 75

means to rapidly reciprocate said radius bar; means acting on said spring carrier beam to counteract excess pressure of said polisher at the extremes of its reverse swings induced by its rapid reciprocation, comprising a vibration controlling adjustably tensioned spring support for the end of said spring carrier beam.

5 4. In a machine for glazing continuously-fed paper or the like comprising a flat paper-supporting bed, a transversely reciprocable radius-bar polisher, a spring carrier beam for the latter provided with tensioning means to regulate the pressure applied to the paper by said polisher, and means to rapidly reciprocate said radius bar; end 10 supporting brackets for said paper-supporting bed having inclined rests adapted to engage only the extreme ends of said supporting bed.

15 5. In a machine for glazing continuously-fed paper or the like comprising a flat paper-supporting bed, a transversely reciprocable radius-bar polisher, a spring carrier beam for the latter provided with tensioning means to regulate the pressure applied to the paper by said polisher, and means to rapidly reciprocate said radius bar; a 20 resilient cushion beneath the bearing surface of said paper-supporting bed, and end supporting brackets for the latter having inclined rests adapted to engage only the extreme ends of said supporting bed.

25 30 6. In a machine for glazing continuously-fed paper or the like comprising a flat paper-supporting bed, a transversely reciprocable radius-bar

polisher, a spring carrier beam for the latter provided with tensioning means to regulate the pressure applied to the paper by said polisher, and means to rapidly reciprocate said radius bar; a 5 resilient cushion beneath the bearing surface of said paper-supporting bed, supporting brackets for the latter having inclined rests engaging only the extreme ends of said supporting bed, and a vibration controlling spring rest for one end of said spring carrier beam.

10 7. In a machine for glazing continuously-fed paper or the like comprising a flat paper-supporting bed and a transversely reciprocated radius bar polisher; a spring carrier beam for the latter provided with intermediate tensioning means to 15 regulate the pressure applied to the paper by said polisher, a fixed support for one end of said beam, and an adjustable resilient support for the opposite end of beam.

20 8. In a machine for glazing continuously-fed paper or the like comprising a flat paper-supporting bed and a transversely reciprocated radius bar polisher; a spring carrier beam for the latter provided with intermediate tensioning means to regulate the pressure applied to the paper by said 25 polisher, a fixed support for one end of said beam, a carrier bracket for the opposite end of said beam having a spring tensioned platform vertically movable in said bracket, and means for adjusting the supporting tension of said platform. 30
